Primary Examiner—Carmen H. Vales-Lado*Attorney, Agent, or Firm*—Peterson, Wicks, Nemer & Kamrath**[57] CLAIM**

The ornamental design for a combined dual armoire, headboard, mirror and bridge, as shown and described.

DESCRIPTION

FIG. 1 is a left side perspective of a combined dual armoire, headboard, mirror and bridge embodying our new design;

FIG. 2 is a front elevation thereof;

FIG. 3 is a left end elevation thereof, with the right end elevation thereof being a mirror image thereof;

FIG. 4 is a top plan thereof;

FIG. 5 is a rear elevation thereof; and,

FIG. 6 is a bottom plan thereof.
